UNITED STATES PATENT OFFICE.

GEORGE WASHINGTON LANCASTER, OF RICHMOND, VIRGINIA, ASSIGNEE TO PERFECTED WINDOW COMPANY, OF RICHMOND, VIRGINIA, A CORPORATION.

WINDOW SASH, SCREEN SASH AND SHUTTER, AND WINDOW FRAME THEREFOR.

Application filed February 20, 1920. Serial No. 369,151.

To all whom it may concern:

Be it known that GEORGE W. LANCASTER, citizen of the United States of America, residing at Richmond, county of Henrico, 5 State of Virginia, has invented a new and useful Window Sash, Screen Sash and Shutter, and Window Frame Therefor, of which the following is a specification.

This invention relates to the art of building construction, and particularly to window sashes, screen sashes and shutters, and more especially to an improved window frame for the support for all three of such closures.

An object of this invention is to provide 15 a sheet metal window frame, constructed to hingedly support a plurality of closures, such as a window sash, screen and shutter, there being means cooperating between the window sash and the window frame acting to lock the window sash in position and at the same time constituting a weather strip.

Another object of the invention is to provide a window sash having guides for the 25 support of a plurality of counter-balanced auxiliary sashes, for closing the opening through the sash.

A further object of the invention consists 30 in the provision of a plurality of auxiliary sashes, counter-balanced in pairs and slideable in guides of a window sash, each pair of auxiliary sashes forming a closure, so that when the auxiliary sashes of all the pairs are closed, intermediate spaces are 35 provided to insure keeping out the cold air, and preventing the escape of the warm air. The auxiliary sashes of the various pairs thereof are adapted to be manipulated for 40 ventilating purposes, as is disclosed in the various diagrammatic views of the drawing.

A still further object of the invention is the provision of a sheet metal window frame having means for the reception of the window trim.

45 A further object of the invention is the provision of means for latching one of the closures, in combination with connections between such closure and another of said closures, so that when the first closure is locked, the second closure will be locked.

An additional object of the invention is the provision of a window frame constructed from sheet metal molding, adapted to form the side and end rails of the frame, in com-

bination with means for connecting the side 55 and end pieces to provide a rigid structure to engage the window opening of the wall.

While the design and construction at present illustrated and set forth is deemed preferable, it is obvious that as a result of a 60 reduction of the invention to a more practical form for commercial purposes, the invention may be susceptible to changes, and the right to these changes is claimed, provided they are comprehended within the 65 scope of what is claimed.

The invention comprises further features and combination of parts, as will be herein-after set forth, shown in the drawings and 70 claimed.

In the drawings:—

Figure 1 is a perspective view of a window constructed in accordance with the invention,

Figure 2 is a vertical sectional view 75 through the window frame, showing the plurality of closures in their closed positions and illustrating the auxiliary sashes in closed positions, and said auxiliary sashes interlocked, in order to insure substantially 80 air tight spaces between the auxiliary sashes,

Figure 3 is a horizontal sectional view on the line 3—3 of Figure 2,

Figure 4 is a view in elevation of the window sash showing a plurality of auxiliary sashes therein, and clearly illustrating the combined locking and weather strip means carried by the sash,

Figure 5 is a diagrammatic view showing 90 the window auxiliary sashes coupled and counter-balanced in pairs differently to that shown in Figure 2, showing certain of the auxiliary sashes as having been moved, to provide a certain amount of ventilation,

Figure 6 is a diagrammatic view showing the auxiliary sashes as having been moved, whereby a different ventilating function may be performed,

Figure 7 is still another diagrammatic 100 view of the auxiliary sashes showing an entirely different adjustment thereof, therefore, it will be seen that an entirely different ventilation of the room may result to that which can be performed by the construction 105 shown in Figure 2.

Figure 8 is an enlarged detail perspective view of one corner of the sheet metal win-

dow frame, showing how one of the side pieces of the frame is connected to one of the end pieces by means of a spotweld,

Figure 9 is a detail perspective view, 5 showing the hinged connection between the screen sash or frame and the window frame,

Figure 10 is an enlarged detail perspective view of the fastening or latch for the screen closure,

10 Figure 11 is a diagrammatic view of a series of auxiliary sashes, showing their normal positions,

Figure 12 is a vertical sectional view through the main window sash showing a 15 plurality of auxiliary sashes mounted for movement vertically therein, in combination with means for connection with the sashes, whereby they are adjustable in variable positions with respect to the adjusting 20 means,

Figure 13 is a vertical sectional view through the main sash showing a plurality of auxiliary sashes, wherein the inner lower and the upper outer sashes are counter- 25 balanced, and wherein the other or intermediate sashes are capable of adjustment in variable positions with relation to each other and with relation to the inner lower and upper outer sashes,

30 Figure 14 is a perspective view of the construction shown in Figure 13,

Figure 15 is a detail view of one of the auxiliary sashes, showing a plurality of window panes, in other words a panel sash, 35 and

Figure 16 is a sectional view on line 16—16 of Figure 15.

Figure 17 is a diagrammatic view showing the series of auxiliary sashes as being 40 adjustable and all in register and interconnected, so as to provide open spaces above and below the sashes.

Referring more especially to these drawings, 1 designates the window frame, preferably constructed of sheet metal, as shown. The frame 1 comprises the top and bottom end pieces 2 and 3 and the vertical side pieces 4 and 5. These side and end pieces are designed to be constructed from suitable 50 sheet metal molding of the character illustrated in the drawings, and according to the size of window frame to be used. The side and end pieces may be cut from the molding according to the dimensions necessary to 55 make window frames to fit various proportions of openings and walls of buildings. The opposed walls of the side and end pieces of the window frame at the corners of the window frame as illustrated in Figure 8, are 60 joined by spot-welds as indicated at 6. These spot-welds are constructed by first notching the ends of the flanges of the end pieces as indicated at 7, so as to receive the ends of the vertical side pieces, that is to 65 say, the flanges at the ends of the vertical

side pieces. Right angle plates 8 are arranged adjacent the inner surface of the adjoining ends of the flanges of the side and end pieces, and by means of the spot-welds as indicated at 6, the side and end pieces are securely and rigidly joined. It is to be noted that when fitting the ends of the flanges of the side pieces in the notches 7, the walls 9 of the side pieces engage the edges 10 at the ends of the top and bottom end pieces. In other words, the end portions of the top and bottom end pieces are bifurcated as indicated, so that the ends of the side pieces will fit the end pieces, whereby the walls 9 and 10 may engage, as shown 80 clearly in Figure 8.

The inner flanges of the side and end pieces of the window frame adjacent their edges are bent to form channels 11, which when the window frame is complete, form a marginal channel on the interior of the room, to receive the ordinary trim or wood-work 12, which surrounds the marginal portion of the window frame not only to assist in holding the frame in position, but also to present a neat appearance and a finish. The brickwork 13 about the marginal edge of the window opening of the wall extends partially into the window frame, as clearly indicated in Figures 2 and 3, so as to hold the frame in position. The channel portion of the inner flange of the window frame is immediately adjacent the brickwork, and by means of the trim, the frame is held in a 90 rigid position.

The inner wall of the window frame or casement (which is engaged by the inner flange of the main window sash) is provided with an angular rabbet 13^a. The wall of the window frame (which is engaged by the window sash) is provided with a substantially U-shaped channel 14. The wall 15 of this channel 14 is deeper than the opposite wall, and the outer wall of the channel 14 at the bottom and one side of the window frame is provided with an angular recess or rabbet 16, the purpose of which will be hereinafter set forth.

Mounted in the window frame is a window sash 17, and the side and end pieces 18 and 19 are cut from sheet metal U-shaped or channelled molding, according to the desired lengths, to fit various sizes of window frames. The top and bottom end pieces are bifurcated at 20, in a manner similar to the bifurcation of the top and bottom end pieces of the frame, to receive the ends of the flanges of the side pieces as indicated in Figure 1. In fact, the channel side pieces engage in the bifurcations, and by means of angle pieces 21, which are spot-welded in place, the side and end pieces of the window sash are securely and rigidly connected, thereby providing a rigid window sash.

The outer flange of the window sash is de-

signed to engage the wall 15 of the U-shaped channel of the window frame, and it is to be noted that one side portion and the bottom portion of the outer flange of said sash 5 engages the angular rabbet 16 of the wall 15, in order to assist in holding the window sash in position. One of the side portions of the inner flange of the window sash is hingedly connected at 22 to the window 10 frame, so that the window sash can swing inwardly, when it is desired to have access to the screen sash or frame and the shutter. Mounted adjacent the inner face of the outer flange of the window sash, that is to say, the 15 bottom portion and one side portion thereof, is a right angle locking member 23.

This locking member 23, which also constitutes a weather strip is provided with arcuate slots 24, receiving guide pins 25. 20 However, one of the guide pins 25 is capable of rotating and is provided with an arm 26 which is pivotally connected to the locking member or weather strip as at 27, so that when rocking the rotatable guide pin, 25 the locking member or weather strip may be moved to an unlocked position or to a locked position. When the locking member or weather strip is in locked position, it protrudes beyond the angular recess 16, so as to 30 protrude further into the channel 14, thereby preventing the window sash from being opened, particularly from the exterior, as there is no way of reaching the rotatable pin, for the purpose of operating the same. 35 The inner end of the rocking pin is provided with a transverse hand piece 28, to be grasped by the hand of an operator so as to rotate the pin, for moving the locking or weather strip into locked and unlocked 40 position.

Secured to the wall 29 of the window sash is a plurality of parallel frames 30, the side and end pieces of which are U-shaped, therefore, are provided with channels 31. Preferably there are six of these channelled frames, though they may be more or less, and these frames are connected to the wall 29 of the sash in pairs. The frames of the inner pair are spaced from the intermediate pair, while the frames of the outer pair are spaced from the opposite side of the intermediate pair. Upper and lower pane or glass receiving auxiliary sashes 32 and 33 are mounted in the inner pair of channel frames of the dominant sash 17, and these auxiliary sash frames are constructed from channel members, so as to receive the window panes or glasses 34 and 35. These auxiliary sashes have their meeting rails provided 45 with interengaging flange connections 36, whereby when said auxiliary sashes are closed, a substantially air-tight joint is provided. Furthermore, this joint will assist materially in holding the auxiliary sashes rigid. Mounted in the outer pair of chan-

nel frames of the dominant sash 17 are upper and lower pane or glass receiving auxiliary sashes 37 and 38, which are similar in construction to those previously described, and their meeting rails are provided with inter-engaging flange connections 39. Mounted in the intermediate pair of channel frames of the dominant sash are upper and lower glass or pane receiving auxiliary sashes 40 and 41, the meeting rails of which 70 also have inter-engaging flange connections 42. It will be noted that by the provision of the three sets or pairs of channel frames with their respective upper and lower auxiliary sashes, intermediate air spaces 43 and 75 44 are provided, acting as cushions for the exterior air and the interior air of the room. The lower rail of the inner sash is provided with suitable hand grips 45, whereby the lower sash 35 may be raised. It will be 80 noted that in Figure 13, the meeting rails of the various auxiliary sashes adjoin each other in a plane, angular, across the dominant window sash, that is to say, in a direction outwardly and upwardly. 85

It will be noted that when the auxiliary sashes are reversed in their positions, in fact, the lower auxiliary sashes moved into their upper positions and the upper auxiliary sashes to lowered positions, as shown in 90 the various diagrammatic views, the interior of the room can be ventilated, owing to the spaces between the adjacent horizontal rails of said sashes. As shown in the diagrammatic Figure 5, the lower inner auxiliary sash is raised and the outer upper auxiliary sash is lowered, therefore, the dead air space 95 between the inner auxiliary sashes and the intermediate auxiliary sashes is destroyed, owing to the passages resulting between the adjacent rails of said auxiliary sashes. The air space between the outer auxiliary sashes and the intermediate auxiliary sashes is likewise destroyed, by reversing the positions of the outer upper and lower auxiliary sashes. 100 If desired, the various auxiliary sashes may be suspended in register with an opening above and below all of the auxiliary sashes. The inner upper and lower auxiliary sashes are connected and counter-balanced one by 105 the other through the medium of the sash cord 45^a which passes over a pulley 46. The outer upper and lower auxiliary sashes are connected and are counter-balanced one 110 against the other by means of a sash cord 47, which passes over a pulley 48. The intermediate upper and lower auxiliary sashes are also connected and counter-balanced by a sash cord 49 passing over the pulley 50. 115 By this arrangement of connecting and counter-balancing the auxiliary sashes (or that shown in Figures 5, 6, 7, 11 and 17) the sashes of each pair thereof can be adjusted 120 in different positions, for ventilating purposes. As shown in the diagrammatic views 125 130

(Figures 5, 6, 7, 11 and 17) the lower inner auxiliary sash is connected and counter-balanced with the upper outer auxiliary sash by means of the sash cord 51, passing over 5 pulleys 52. The upper inner auxiliary sash is connected to the outer lower auxiliary sash by a sash cord 53 passing over pulleys 54, and they are counter-balanced thereby. The upper and lower intermediate auxiliary 10 sashes are connected and counter-balanced by means of the sash cord 55 passing over a pulley 56. This arrangement permits the various auxiliary sashes to be moved to different positions to those assumed by the 15 sashes shown in Figure 2, thereby enabling a different arrangement of ventilation. It is obvious that the auxiliary sashes may be connected and counter-balanced in any other suitable manner. In other words, the invention, particularly pertaining to the auxiliary sashes is not to be limited in any way in so far as the connections and counter-balancing of the sashes are concerned. The manner of 20 counter-balancing the auxiliary sashes, and the arrangement of them in pairs, so as to provide the intermediate air spaces constitute an improvement over the construction and arrangement of dominant sashes, such as shown in the co-pending application, filed 25 30 August 2nd, 1919, Serial Number 314,910 in the name of George W. Lancaster, and which application has matured into patent issued December 7, 1920, Patent Number 1,361,163.

The marginal rabbet or channel 57 (which 35 is angular in cross section) receives a screen frame 58. Adjacent the upper part of the channel or rabbet 57, a pair of suspension or hinged hooks 59 is secured preferably by spot-welding, though it is obvious 40 that they may be otherwise connected. These hooks are in the form of plates bent upon themselves, the bends thereof acting as supporting hooks 60. The 45 plates forming the suspension or hinge 50 hooks have their upper parts recessed as indicated at 61 so that when the plates are bent to form the hooks these recesses will be positioned adjacent the sides of the hook, thereby permitting the bends proper of the 55 plates to protrude upwardly beyond the recesses to form lugs 62.

The screen frame is also designed to be 55 constructed of sheet metal, and secured in any suitable manner to the upper rail of the screen frame, preferably by spot-welding, are hanger plates 63. These hanger plates are bent to form the upwardly extending parts 64 which are provided with slots 65 which engage the hooks of the plates 59, 60 thereby hingedly mounting the screen frame. It will be noted that when the screen frame is swung outwardly it may be easily detached from the hook. Hingedly 65 connected at 67 to the upper part of the outer portion of the window frame is a shut-

ter 66 similar to those in patents issued to Cecil J. Lancaster on the 21st day of May, 1918, Patent Number 1,267,087 and to Wesley Price Shomaker, issued April 29, 1919, Patent Number 1,302,093, both being owned by the Perfected Window Company (incorporated), which is controlled by George W. Lancaster. This shutter is hinged, in order to swing outwardly, when it is desired to open the same, and to overlie the screen frame when it is closed. Secured to the inner portion of the lower face of the shutter are angle plates or hooks 68, which are engaged by the lower portion of the screen frame 58, when the shutter and the screen frame are closed. However, when the shutter is swung open the screen frame will also be moved to an open position. When the shutter is swung open far enough, the screen frame will disengage from the angle plates or hooks 68 owing to the different arcuate movements of the shutter and the screen frame. In other words, the screen frame and the shutter are mounted to move through converging arcs, therefore, when the shutter is moved to an open position far enough the screen frame will disengage from the angle plates or hooks 68. When the shutter is moved to an open position far enough to permit the screen frame to disengage, the screen frame may be moved inwardly again and fastened, and in such a case the shutter may be supported in an open position by means of the brace 69 shown in Figure 1.

It is obvious that when it is necessary to close the shutter, the screen frame must be swung open again until its lower end is in a position to engage the angular plates or hooks 68, and then the brace 69 is disconnected from the exterior of the window frame, after which the screen frame and the shutter may be moved inwardly together. Secured at 70 to the lower part of the window frame is a keeper 71. This keeper comprises a plate, which has an upwardly extending flange 72 disposed at an angle to the horizontal position of the lower part of the window frame. This flange 72 is formed by bending the plate upon itself as shown in the detail view in Figure 10 of the drawing. A latch is pivotally secured by means of a screw 73, to the lower rail of the screen frame, and this latch has a handle portion 74, and a keeper engaging part 75, which is curved as shown.

This latch is constructed from a single piece of sheet metal as disclosed in the drawings. The keeper engaging part, when the latch is swung in one direction, is designed to engage the inclined flange 72, thereby latching the screen in a closed position, and when so closed the shutter will be held in a closed position owing to the angular plates or hooks 68. When the latch is moved in the opposite direction, the keeper engaging part

75 will disengage the flange 72, thereby permitting the screen frame to be moved outwardly.

Referring to the construction shown in Figure 12, the main sash 80, which is similar in some respects to the main sash heretofore described, has its auxiliary sashes arranged in spaced relations to provide the air spaces or pockets heretofore referred to. These auxiliary sashes are also inter-locked as shown at 81, and are mounted in guides 82. Additional guides 83, 84 and 85 are adjacent the guides in which the auxiliary sashes are mounted, and mounted in the guides 83, 84 and 85 are rods 86, 87 and 88 and connecting the rods 86, 87 and 88 with the upper parts of the upper auxiliary sashes are ropes or cables 89. Carried by the side rails of the lower auxiliary sashes are projecting arms 90, 91 and 92. Certain of the flanges of the guides for the rods 86, 87 and 88 having openings 94, which are adjacent the arms 90, 91 and 92. The cables which connect to the rods pass over the pulleys 95 which are journaled in any suitable manner, as shown, in the channel of the upper part of the main sash, and are connected to the upper ends of the upper auxiliary sashes. It is obvious that by removing the lower rod 86 from its guides through the lowermost notches of one of the flanges of the guides for the rod and in setting it through the succeeding notch or notches, the rod 86 may be disposed under the arms 91, thereby lowering the upper inner auxiliary sash, in fact lowering it a distance substantially equal to the distance between the pins 91 and the bottom of the main sash, thereby breaking the air pocket between the inner sashes and the intermediate sashes. When the rod 86 is disposed in engagement with the arms 91 it is obvious that the lower inner auxiliary sash may be adjusted, by applying pressure on the rod 86 under the pins 91 raising the lower inner auxiliary sash, and when raised, the upper inner auxiliary sash will be lowered correspondingly. However, when raising the lower sash by engaging the rod 86 with the arms 91 of the inner lower sash, the upper inner auxiliary sash may be lowered to an open position for a distance equal to the space between the arms 91 and the bottom of the main sash. Should the inner lower auxiliary sash be moved by applying upward pressure on the rod 86, when engaged under the arms 91, the upper inner auxiliary sash may be lowered for its full movement, while the inner lower sash will be raised to a position with its upper edge spaced a distance from the upper rail of the main sash substantially equal to the distance between the arm 91 and the arm 90.

After manipulating the inner auxiliary upper and lower sashes, the intermediate auxiliary upper and lower sashes may be

likewise adjusted. If desired, the rod 86 or the rod 87 or the rod 88 may be moved to engage any of their respective arms 90, 91 and 92, in order to raise and lower the inner auxiliary sashes. In other words, said auxiliary sashes are capable of adjustments in variable positions relative to each other, or are capable of adjustments to corresponding positions. It is obvious that this construction of the auxiliary sashes is equally as well adapted for use in connection with the window construction shown in Figures 1 and 2. In fact, the main sash shown in Figure 12 is similar in every respect to the main sash shown in Figures 1 and 2, with the exception that the sash in Figure 12 is equipped with different auxiliary sashes, and it is obvious that the construction in Figure 12 can be used in Figure 1 or in Figure 2.

In Figure 13, the auxiliary sashes are arranged in stepped relation similar to the construction shown in the patent to George W. Lancaster of December 7, 1920, Patent No. 1,361,163, but in the present instance the upper and lower auxiliary sashes are capable of adjustments in variable positions relative to each other, in a manner similar to the adjustments of the auxiliary sashes in Figure 12. The auxiliary sashes 96, 97, 98 and 99 in Figure 13 have inter-locked connections 100, and the two intermediate auxiliary sashes in Figure 13 are counter-balanced, by means of the cable or rope 101, passing over the pulley 102, which is journaled in the upper part of the main sash in any suitable manner. The main sash in Figure 13 is provided with guides 103 which are similar to the guides 83 of the sash in Figure 12. Mounted in the guides 103 normally in the lower portion thereof is a sash adjusting rod 104, which is connected to and counter-balanced with the uppermost auxiliary sash 99 by means of the cable or rope 105, which passes over the pulleys 106, which are journaled in the upper part of the main sash in any suitable manner. It is to be observed that by removing the adjusting rod 104 from its guides, by passing it through any one of the notches 107 of certain of the flanges of the guides 103, and placing it under either one of the upper lateral arms 108 of the lower auxiliary sash, the upper auxiliary sash may be adjusted in variable positions with relation to the lower auxiliary sash. By causing the rod 104 to engage under the lower arms 109 of the lower auxiliary sash, the lower and upper auxiliary sashes may be opened correspondingly. The various auxiliary sashes shown in Figures 1, 2, 12 and 13 extend the entire width of the dominant or main sash. However, each of these auxiliary sashes may be made up in panels, such as shown in Figures 14, 15 and 16. In fact, the auxiliary sashes are in the form of channel irons, as shown in Figure 16 to receive

the pane of glass 110. These channel frames have channel guides 111, near one end of the frame to receive the panes of glass 112 and 113. The channel frame at one end is 5 cut away or slotted as shown at 114 so that the pane of glass 112 may be easily removed for repair or for the insertion of a new pane. The channel frame is also provided with spaced vertical strips 115. The other end 10 of the channel frame has a vertical cut away portion or slot 116, through which the panes of glass 110 and 113 may be inserted, or removed, in other words removed for repairs or for the insertion of new panes. It will 15 be noted that the adjacent edges of the panes 110 and 113 engage between the vertical strips 115 thereby holding them in position. The panes of glass are designed to engage the channels of the channel frames frictionally, in order to remain in position.

The invention having been set forth, what is claimed as new and useful is:—

1. In a device for the purpose indicated, a window casement, an outer closure swingingly mounted therein and tending to a closed position, a second closure swingingly mounted in the casement, latching connections between the two closures, said closures swinging through intersecting arcs, whereby 25 when the closures are being opened the latching connections may disconnect, and when the outer closure is moving toward a closed position, it may move the second closure to a closed position, thereby causing 30 the latching means to reconnect, the second closure being movable to a closed position independently of the outer closure, which may remain open.

2. In a device for the purpose indicated, 40 a window casement, an outer closure swingingly mounted therein and tending to a closed position, a second closure swingingly mounted in the casement, latching connections between the two closures, said closures swinging through intersecting arcs, whereby 45 when the closures are being opened the latching connections may disconnect, and when the outer closure moves toward a closed position it is adapted to automatically bear against and move the second closure to a closed position, thereby causing the latching connections to reconnect, the second closure being movable to a closed position independently of the outer closure which 50 may remain free or be held open, and means for latching the second closure to the casement.

3. In a device for the purpose indicated, 60 a window casement, an outer closure mounted therein and tending to a closed position, a second closure mounted therein adjacent the first closure, said closures being mounted to swing through intersecting arcs, coupling means between the free unattached ends of 65 both closures to connect and disconnect when

the closures are being closed and opened, the outer closure when moving toward a closed position being adapted to engage upon and actuate the second closure toward a closed position, the second closure being 70 movable to a closed position independently of the outer closure, which may remain in an open position.

4. In a device for the purpose indicated, 75 a window casement, an outer closure mounted therein and tending to a closed position, a second closure mounted therein adjacent the first closure, said closures being mounted to swing through intersecting arcs, coupling means between the free unattached ends of 80 both closures to connect and disconnect when the closures are being closed and opened, and means for latching the second closure when closed, the outer closure when moving toward a closed position being adapted to 85 engage upon and actuate the second closure toward a closed position, the second closure being movable to a closed position independently of the outer closure, which may remain in an open position.

5. In a device for the purpose indicated, 90 a window casement, an outer closure mounted therein and tending to a closed position, a second closure mounted therein adjacent the first closure, said closures being mounted to swing through intersecting arcs, coupling means between the free unattached ends of 95 both closures to respectively connect and disconnect when the closures are being closed and opened, the outer closure when moving toward a closed position being adapted to engage upon and actuate the second closure toward a closed position, the second closure being movable to a closed position independently of the outer closure, which may remain in an open position.

6. In a device for the purpose indicated, 100 a window casement, said casement having an inner rabbet provided with a marginal channel, said casement having a pair of outer marginal adjacent rabbets, the outer portion of the casement having a flange engaging the outer surface of the wall of a building, the inner flange of the casement having a marginal channel adapted to receive the trim of the window.

7. A window frame adapted to engage an opening in a wall and provided with a plurality of rabbets, an inner closure mounted to swing into and out of engagement with one of said rabbets, outer and intermediate closures mounted to swing into and out of engagement with other of said rabbets, means for locking the intermediate closure, and a connection between the intermediate 115 120 125 130 135

closure and the outer closure, whereby when the intermediate closure is locked, the outer closure is likewise locked.

8. A window frame to engage a window opening in a wall and provided with an inner rabbet facing inwardly, and outer and intermediate rabbets facing outwardly, a plurality of closures to engage said rabbets respectively, one of said closures to swing

10 open inwardly and the other two to swing open outwardly, the outermost of said outwardly swinging closures, when open, tending to move to a closed position and thereby bear against and close the other outwardly moving closure, said other outwardly opening closure being movable to a closed latched position in engagement with the intermediate rabbet without closing the first outwardly opening closure.

20 9. A window frame to engage a window opening in a wall, and provided with an inner rabbet facing inwardly, and outer and intermediate rabbets facing outwardly, inner and outer and intermediate closures 25 swingingly mounted to engage said rabbets respectively, the intermediate and outer closures movable through converging arcs, the intermediate closure movable to a closed position in engagement with the intermediate rabbet, while the outer closure remains open, means for locking the intermediate closure, and a separate connection for automatically connecting the ends of the intermediate and outer closures.

30 10. A window frame having an inwardly facing rabbet and provided with intermediate and outer rabbets facing outwardly, a main sash closure having vertical guides at opposite side rails mounted to swing open inwardly from the inwardly facing rabbet, screen and shutter closures respectively mounted in the outwardly facing intermediate and outer rabbets and adapted to swing outwardly, the shutter, when the closures 40 are open, tending to move to a closed position and thereby move the intermediate closure to a closed position, said screen closure being movable to a closed position without closing the shutter closure, a plurality of auxiliary sashes mounted in said guides, and means connecting said auxiliary sashes for counterbalancing them relatively to each other.

45 11. A window frame having an inwardly facing rabbet and provided with outwardly facing outer and intermediate rabbets, a dominant sash including a plurality of guides mounted to swing inwardly from the inwardly facing rabbet, screen and shutter closures mounted respectively in the outwardly facing intermediate and outer rabbets and adapted to swing outwardly, said shutter closure when open tending to move 55 toward a closed position and adapted to bear against the screen closure, said screen clo-

sure adapted to assume a closed position independently of and without closing the shutter closure, a plurality of auxiliary sashes mounted in said guides, and means connecting said auxiliary sashes for counterbalancing them relatively to each other.

50 12. A window frame having an inwardly facing rabbet and provided with outwardly facing outer and intermediate rabbets, a dominant sash including a plurality of guides mounted to swing inwardly from the inwardly facing rabbet, screen and shutter closures mounted respectively in the outwardly facing intermediate and outer rabbets and adapted to swing outwardly, said shutter closure when open tending to move 55 toward a closed position, thereby bearing upon the screen closure if open, said screen closure adapted to assume a closed position independently of and without closing the shutter closure, a plurality of auxiliary sashes mounted in said guides, and means connecting said auxiliary sashes for counterbalancing them relatively to each other, said screen and shutter closures being suspended 60 to move through converging arcs, means separably connecting the screen and shutter closures, the latter constituting an awning when it remains open.

65 13. A window frame including a rabbet, and provided with a channel adjacent the rabbet and extending along one side and the bottom of said frame, a sash swingingly engaging said rabbet, a right angle weather strip mounted adjacent one side and bottom of said sash and guided into and out of engagement with said channel, guide pins for said strip, and a rocking pin provided with a radial arm connection with said weather strip to move it into and from the channel.

70 14. A window frame having a rabbet and provided with a channel adjacent the rabbet and extending along one side and the bottom of said frame, a sash operating into and from the rabbet, a right angle weather strip having its arms engaging the perpendicular and horizontal portions of said channel, said weather strip having guide slots, pins engaging through the slots for guiding the weather strip operatively into and from the channel, one of said guide pins having an arm connection with the right angle weather strip and provided with means for rocking the same to move the weather strip toward and from the channel.

75 15. A window structure comprising a series of lower sashes, a series of upper sashes, both series being of equal number, each sash of one series being associated with a sash of the second series, guides positioned above the sashes of each associated pair, a pair of flexible members connecting the sashes of each associated pair and passing over said guides to cause the sashes of said pair to move in unison and in reverse directions, an

element connecting the flexible members of each pair, spaced means carried by each sash of one series, with which the respective element may selectively connect to vary the relation of its sashes with each other, thereby permitting of a selective adjustment of the respective sashes of the associated pairs.

16. In a window structure, a frame provided with side guides, upper and lower sashes movable in certain of said guides, flexible members connecting said sashes, means connecting said members and movable with said flexible members in other of said guides, guides for said flexible members, spaced immovable means carried by one of the sashes to which said means may selectively connect for varying the relation of the sashes for effecting selective relative 20 adjustments of the sashes.

17. In a window structure, a frame provided with side guides, upper and lower sashes mounted in certain of said guides, flexible members connected to the upper sash, 25 guides for the flexible members, a plurality of immovable devices carried by the lower sash, an element connecting said flexible members and movable in other of said side guides and adapted for selective cooperation 30 with said devices for varying the relation between the sashes, whereby selective relative adjustment of the sashes may be effected.

18. In a window structure, a frame provided with side guides, upper and lower sashes mounted in certain of said guides, flexible members connected to the upper sash, guides for the flexible members, a plurality of sets of devices carried by the lower sash, an element connecting the flexible 40 members and adapted for selective cooperation with said devices and movable in other of said side guides for varying the relation between the sashes, whereby selective relative adjustment of the sashes may be effected, the guides for said element having means permitting the element to be disengaged from one set of devices and re-engaged with another set, and vice versa.

19. In a closure structure, a frame, outer 50 and inner movable closure members mounted therein to swing outwardly from closed positions through divergent arcs and to tend when open to move to closed positions, and means carried by one of said closures 55 to engage the other automatically, as said closures approach their closed positions, to prevent their relative separation.

20. In a device for the purpose indicated, the combination with a casement, of an inner closure swingingly mounted in the casement, an outer awning closure swingingly suspended from the upper part of the casement to swing outwardly, an intermediate closure suspended from the upper part of 65 the casement to swing outwardly, means for

connecting the lower ends of the intermediate and outer closures, and means for latching the intermediate closure to the casement.

21. In a device for the purpose indicated, the combination with a casement, of an inner closure swingingly mounted in the casement, an outer awning closure swingingly suspended from the upper part of the casement to swing outwardly, an intermediate closure suspended from the upper part of the casement to swing outwardly, means for connecting the lower ends of the intermediate and outer closures, and means for latching the intermediate closure to the casement, said inner closure constituting closing means adapted, when fully closed, to prevent access to the latching means of the intermediate closure.

22. In a closure structure, a frame, outer and inner movable closure members mounted therein to swing outwardly from closed positions through divergent arcs and to tend when open to move to closed positions, and means carried by one of said closures to engage the other automatically, as said closures approach their closed positions, to prevent their relative separation, and means for latching the inner closure member to the frame.

23. In a closure structure, a frame, an inwardly swinging inner closure member, outer and intermediate closure members correspondingly mounted in the frame to swing outwardly from closed positions through divergent arcs, the outer member, when open, tending to move to a closed position, and means carried by the outer closure to engage the intermediate closure automatically as said closures approach their closed positions to prevent their relative separation, means for latching the intermediate closure to the frame, said inner closure constituting closure means adapted, when fully closed, to prevent access to the latching means of the intermediate closure.

24. In a closure structure, a frame, outer and inner movable closure members mounted therein to swing outwardly from closed positions through divergent arcs and to tend when open to move to closed positions, and means carried by one of said closures to engage the other automatically, as said closures approach their closed positions, to prevent their relative separation, the inner closure being movable to a closed position independently of the outer closure, which is then adapted to remain open.

25. In a window structure, a frame provided with opposed guide grooves, two pairs of sashes slidable in said frame, each of said sashes being of substantially one-fourth the height of the window opening, guide means carried by the upper portion of said frame, flexible elements connected to one of said

sashes and trained over said guide means, means connecting said elements and slidable in said grooves, spaced supporting means on another of said sashes, and means whereby said supporting means may be selectively engaged by said connecting means to counter-balance the last two sashes mentioned in relatively variable relation.

In witness whereof, in the presence of two witnesses, the inventor's signature is here- 10 unto affixed.

GEORGE WASHINGTON LANCASTER.

(Two witnesses):

A. D. LIVESAY,
M. L. WILLIAMS.
